H. M. FOXON

SPIRAL PUTTEE

Filed Sept. 28, 1922

UNITED STATES PATENT OFFICE.

HORACE M. FOXON, OF BROCKTON, MASSACHUSETTS, ASSIGNOR TO LAPWORTH WEBBING COMPANY, OF STOUGHTON, MASSACHUSETTS, A CORPORATION OF MAINE.

SPIRAL PUTTEE.

Application filed September 28, 1922. Serial No. 591,173.

To all whom it may concern:

Be it known that I, HORACE M. FOXON, a citizen of the United States, residing at Brockton, in the county of Plymouth and 5 State of Massachusetts, have invented a new and useful Spiral Puttee, of which the following is a specification.

This invention relates to a puttee adapted to be used for military uses and for traveling, camping and the like. The ordinary puttee, that is, a puttee of the so-called spiral kind, is wound around the ankle and leg and is fastened at the top. On account of the unyielding nature of the material it 15 binds the leg after awhile, decreases the circulation, and becomes uncomfortable. If wound loosely enough to avoid these difficulties, it is difficult to secure it effectively so that it will retain its position.

20 The principal object of this invention is to provide a spiral puttee of such a character that it will not have either of these defects. I accomplish this by making the body of the puttee of a textile material which will be 25 capable of stretching longitudinally but not laterally.

Reference is to be had to the accompanying drawings, in which

Fig. 1 is a side view of a puttee constructed in accordance with this invention, shown in position on the leg;

Fig. 2 is a full size view of the end of such a puttee;

Fig. 3 is a similar view showing the same 35 stretched out to its limit, and

Fig. 4 is a transverse sectional view on the line 4—4 of Fig. 2.

I form the puttee of a single long strip 9 of woven fabric having longitudinal elastic 40 threads 10 woven in as warp threads, spaced equal distances apart across it, and woven in a stretched condition so that when the fabric is taken off the loom, these threads will contract and the cloth between them 45 will be puckered up or shirred so as to form a fabric having considerably greater thickness than the stretched fabric. The edges

are finished by weaving a selvage in the usual way and one end of the puttee is formed by making a hem across it. The 50 other end is formed V-shape by folding over the two corners 11 to meet at the center and a non-elastic strap 12 is sewn over these raw edges to hide them and fix the strap to the end of the puttee. This strap extends from 55 its center a sufficient distance to permit of its being used as the ordinary strap.

In use, the puttee is placed in position in the usual way and wound around, as shown in Fig. 1, all the way to the top. Here the 60 strap is used for fastening it in the manner that has been common heretofore. This puttee is not only soft and pliable but it is capable of stretching longitudinally so it can be laid on the surface with any desired 65 degree of tightness and yet, unless stretched to its limit, will not bind the limb and cause any stoppage of circulation through it. It is light and comfortable and also porous, especially when a little stretched, yet it accomplishes all the objects of the ordinary puttee 70 and avoids the uncomfortable features above mentioned.

Although I have illustrated and described only a single form of the invention, I am 75 aware of the fact that modifications can be made therein by any person skilled in the art without departing from the scope of the invention as expressed in the claim. Therefore, I do not wish to be limited to all the 80 details of construction herein shown and described but what I do claim is:—

As an article of manufacture, a woven puttee in which elastic warp threads are 85 woven in it in a stretched condition and spaced at distances apart all the way across the fabric, whereby when the tension is removed these warp threads will contract and gather or shirr the rest of the fabric up between them, said puttee being transversely 90 non-elastic.

In testimony whereof I have hereunto affixed my signature.

HORACE M. FOXON.
